Primary Examiner — Paula Greene(74) *Attorney, Agent, or Firm* — Brooks Kushman P.C.(57) **CLAIM**

The ornamental design for the earbud, as shown and described.

DESCRIPTION

FIG. 1 is a perspective view of the earbud thereof;

FIG. 2 is a top plan view thereof;

FIG. 3 is a bottom plan view thereof;

FIG. 4 is a left side view thereof;

FIG. 5 is a right side view thereof;

FIG. 6 is a rear view thereof; and,

FIG. 7 is a front view of the present invention.

The broken lines are for illustrative purposes only and form no part of the claimed design.
